(57) **CLAIM**

I claim the ornamental design for the palm trimmer, as shown
and as described.

DESCRIPTION

Proper care of Palm Trees requires that some clumping Palms
may need to be thinned out or new growth pruned off if the
Palm Trees are getting too big for the space in which the
Palms are growing. Unfortunately, removing branches
(fronds), spikes, palm flowers and fruit stalks from a Palm
Tree can be a dangerous task in that a user can get their hand
cut by the spikes and sharp edges. As such, there is a need in
the art for a palm trimmer, which will allow a user the ability
to remove the branches (fronds), spikes, palm flowers and
fruit stalks of the Palm by positioning the blade of the palm
trimmer over a branch and pulling back on the handle of the
palm trimmer to snapping the branch.

FIG. 1 is a perspective view of the palm trimmer;

FIG. 2 is a front view of the palm trimmer;

FIG. 3 is a back view of the palm trimmer;

FIG. 4 is a side view of the palm trimmer;

FIG. 5 is a other side view of the palm trimmer;

FIG. 6 is a top view of the palm trimmer; and,

FIG. 7 is a bottom view of the palm trimmer.

The handle is shown broken away to indicate that no particular
length is claimed.
